(57) **CLAIM**

The ornamental design for an inductive charger, as shown and described.

DESCRIPTION

FIG. 1 is a rear view of the inductive charger.

FIG. 2 is a left side view of the inductive charger, the right side being a mirror image thereof.

FIG. 3 is a front view of the inductive charger.

FIG. 4 is a bottom view of the inductive charger.

FIG. 5 is a top view of the inductive charger.

FIG. 6 is a top, front, left perspective of the inductive charger.

FIG. 7 is a right side view of the inductive charger, shown in a vertical standing position, the left side view of the vertical standing position being a mirror image thereof.

FIG. 8 is a top, right perspective view of the inductive charger, shown in a vertical standing position.

FIG. 9 is a rear view, of the inductive charger, shown in a horizontal standing position.

FIG. 10 is a top, rear perspective view of the inductive charger, shown in a horizontal standing position; and,

FIG. 11 is a top, right exploded view of the inductive charger, shown in a vertical standing position.
